UNITED STATES PATENT OFFICE.

BENJAMIN F. FAUNCE, OF JOHNSTOWN, PENNSYLVANIA.

WHEEL MILL.

Application filed August 27, 1921. Serial No. 496,124.

To all whom it may concern:

Be it known that I, BENJAMIN F. FAUNCE, a citizen of the United States, and a resident of the city of Johnstown, county 5 of Cambria, and State of Pennsylvania, have invented certain new and useful Improvements in Wheel Mills; and I do hereby declare the following to be a full, clear, and exact description of the invention, such 10 as will enable others skilled in the art to which it appertains to make and use the same.

My invention relates in general to improvements in the construction of wheel mills which are adapted to roll metal car 15 wheels or other similar annular bodies, but for the sake of convenience of description herein I will refer only to wheels.

Heretofore mills of this character have 20 had a framework formed of a large number of parts, secured together by bolting or otherwise, the front of which was only bolted to the base plate forming flexible cantilevers, these and the other portions of 25 the structure carrying the working parts, whereas I make a solid front framework connected at the top and bottom to the base and top frames to make a rigid construction.

With the prior constructions the springing or looseness of the framework allows the 30 working portions to move from their proper places or out of adjustment, thereby spoiling the work, and in addition to this the prior constructions have been of such a 35 character as to require a large amount of time and labor in making changes and necessary adjustments of rolls. In order to obviate this I form the front portion of my apparatus substantially integral, tied together 40 above and below, and mount upon it the working parts in such a way that the stresses of use are taken up by the solid front framework without the maladjustments above referred to, thereby making a 45 compact and solid structure which holds the working parts in position at all times.

Although I have shown my front frame work as composed of two sections, this is 50 so drawn merely for the purpose of ease of making the castings and machining the same, and these two sections are held together by a very few bolts, and when the front frame so composed is secured together and to the other parts of the framing it is substantially integral.

I may, however, make the front frame completely integral and omit the flanges, separator and bolts which secure the two halves together, thus making it entirely integral and in one piece and well adapted to 60 withstand the stresses and strains of use.

In addition, my construction is of a simple character and my front framework, comprising front apron and headblock portions, 65 is secured to the other parts, such as the rear frame and the base plate, by quick-acting bolts, so that it can be disassembled for replacement and adjustment of the working parts and reassembled in one-third the time 70 that is required with the old structures.

With the old structures any movement of the headblocks or similar portions in relation to each other or to the working portions, such as web rolls, back or tread rolls, or 75 guide rolls will cause the wheel which is being rolled to become nonuniform in dimensions, and in consequence it is rejected and is only scrap, whereas with my construction the working parts are held so firmly in position that these troubles are entirely 80 obviated.

In prior constructions the minor in and out adjustments of the edging rolls were obtained by mounting them on eccentric pins, 85 which pins when rotated slightly move these rolls inwardly or outwardly as desired, but this adjustment was insufficient and shims were required to line the brackets of the edging rolls, necessitating much loss in 90 time and labor. This construction has been 90 improved by me whereby I mount the edging rolls on adjustable shanks with screw movement of sufficient extent for all adjustments longitudinally.

Another difficulty with the prior type of 95 edging rolls is the fact that in rolling wheels of different diameters the edging rolls were non-adjustable in a direction approximately radial to the wheel, with the result that with 100 wheels of different diameters the angularity of the axes of the edging rolls caused pulling and tearing action on the wheel rim, which distorted the wheel and produced slivers on it. I obviate this difficulty by 105 mounting my edging rolls so that their axes can be adjusted with respect to the radius of the wheel, the rim of which is thereby rolled approximately on circumferential lines, thus obviating the destructive action 110 above mentioned, and this avoids the drag-

ging and consequent slivering of the wheel rims.

In addition to this the edging rolls are not required to be the same distance apart from the center line for all wheels on account of the varied design of different wheels, and my method of separately adjusting these edging rolls applies itself readily to this requirement.

10 In my construction the right and left hand sections of the combined headblocks and apron forming the front frame are substantially integral with each other, and their relations to each other and other portions are such as to firmly maintain them in position and thereby hold the working portions mounted therein in rigid adjustment as desired, and the headblocks or aprons each have integral pads on which the 15 wheel mandrel rests and these are integral with the framework which carries the edging and guide rolls.

The front apron, which comprises the headblocks and wheel mandrel supports, 20 supports the edging rolls with their adjusting mechanism and carries the guid rolls, is incorporated substantially as one unit, so that it may be easily, quickly and securely attached to or detached from the top and 25 bottom plates of the mill frame, which thereby reduces the time necessary to change the working parts and insures proper relative alignment thereof.

30 In addition to the difficulty of slivering the rims and the destruction of the metal of the wheel in prior practice, my adjustment of the edging rolls to the substantially radial position of their axes with respect to the wheel, also eliminates excessive wear on the edging rolls in addition to preventing 35 slivering due to their incorrect position.

Having thus given a general description of my invention, I will now, in order to make the matter more clear, refer to the 40 annexed two sheets of drawings, which form part of this specification, and in which like characters refer to like parts.

Figure 1 is a side elevation of my improved wheel mill; Figure 2 is a vertical sectional elevation of the apparatus taken on the line II—II of Figure 1; Figure 3 is a detail view showing the mounting of one of the idler gears which meshes with a pinion on the drive shaft and a gear on the 45 shaft of the adjusting screw for advancing or retracting the edge roll brackets; Figure 4 is a detail view of the indicator dial; Figure 5 is a detail view illustrating the position of the web and tread rolls when in 50 operation; Figure 6 is a vertical longitudinal sectional elevation of one of the edge rolls, the edge roll bracket for holding the same, and the adjusting means for the edge rolls; Figure 7 is a horizontal longitudinal 55 sectional elevation of the mechanism shown

in Figure 6 taken at right angles to that of Figure 6; Figure 8 is a vertical transverse section through the edge roll adjusting mechanism taken on the line VIII—VIII of Figure 7; and Figure 9 is a front elevation of the edge rolls illustrating a modified form of rotary adjustment for them.

Referring now to the characters of reference on the drawings: 1 indicates the rear framing of the mill in general; 2 are the 75 slideways thereof upon which the tread or back roll is mounted; 3 is the tread or back roll; 4 is the front frame or head block composed of two sections, having the mandrel supports integrally combined with the 80 other portions thereof. The right and left hand sections of these portions 4 are secured together by the bolts 5 and 6, which latter are provided with separators or spacers 7 as illustrated. 8 are keys or projections between the main frame and the headblock 4 adapted to hold these parts in proper relative position. 9 is the support and guideway for the arbor or mandrel on which the wheel in process of rolling is held, formed 90 integral with the frame 4; 10 are wearing plates or shims in the guideway for supporting the arbor and more or less of these are used or they may be of different thicknesses and removable and replaceable to accommodate wheels of different sizes and diameters; 11 is the mandrel or arbor on which the wheel and blank is mounted during the process of rolling. 12 indicates the wheel blank, which is of smaller diameter 100 than the finished wheel, in position for rolling and 13 are the edging rolls which operate upon the rim of the wheel and are adjusted inwardly and outwardly and to radial position. 14 are the shafts on which the 105 edging rolls are rotatably mounted; 15 are brackets which support the edging roll shafts; 16 are the shafts or adjustable shanks of the edging roll brackets adapted to be adjusted inwardly or outwardly or rotated 110 within their supports to produce the radial position of the roll axes as desired. 17 are sleeves mounted on 16; 18 are sockets in portions of the headlock or front frame 4 which receive the sleeves 17. 19 is a feather key slidably connecting the portions 16 and 17; 20 is a nut mounted in the shank 16, which, in connection with the adjusting screw 21 and attachments is adapted to feed the shank inwardly or outwardly to adjust 115 the edging rolls as necessary; 22 is a collar on the screw 21 to withstand the thrust thereof and on the extending end portion 23 of the screw 21 is mounted the gear 24. 25 is a pipe for feeding grease or lubricating 120 oil to the moving portions. A flange 26 is attached to or part of the adjusting sleeve 17, in which are formed a number of bolt holes 27 as illustrated, through which bolts 28 are passed in order to secure the parts in 125 130

the relation desired. 29 is a flange on part of the mill framing which also has a series of holes therein. These holes in the flanges 26 and 29 are in staggered relation with 5 more holes in one portion than in the other, so that by moving the parts one hole registers with another hole and the bolt inserted so that adjustment can be made of the edging rolls 13. By means of this adjustment, 10 the axes of the edging rolls can be set within two or three degrees. The flange 26 is provided with a socket 30 in which a bar can be inserted to rotate it as desired for adjustment. The shank 16 is mounted in the 15 bushing 17 in such a manner that it may be moved endwise therein, and by reason of the feather it can be rotated with the bushing 17. Integral bosses 31 are also provided, in which are mounted stud bolts 32 provided 20 with collars 33 and on which the idler gears 34 are mounted and secured, these being arranged to gear with the pinion 35 on the drive shaft 36. The stud bolts 32 are provided with washers 37 on their outer ends as 25 illustrated. 38 is an indicator dial adapted to show the position of the edging rolls, which dial may be graduated temporarily from time to time to suit the work. This dial is provided with an indicator hand 39 30 mounted on the cylindrical projection 40. The drive shaft is provided with driving gear generally indicated as 41, operated by the motor 43 geared thereto. 42 are the web rolls which are converging and tapered 35 as illustrated and provided with driving means (not shown).

Referring now to Figure 9, which shows an alternate arrangement of adjustment for the edging rolls:—this is provided with 40 journal bearings 44, in which is mounted a worm 45, provided with a manually operated crank arm 52. The sleeve 17 is provided with a flange 47 formed as a sector of a worm wheel and provided with marginal teeth 46 45 which engage with the thread of the worm gear 45. 47 may also be provided with slight corrugations 48 and corresponding corrugated washers 49, which, when the sleeve 17 is adjusted by means of the crank arm 52, 50 can be securely clamped in place by means of the bolt 50, the corrugated washers 49 and the corrugations of the flange 47. The flange 47 is also provided with a curved slot 51 through which the bolt 50 is passed. 55 By means of this mechanism I can adjust the radial position of the edging rolls to the fraction of a degree. The corrugations may be omitted if desired.

The wheel after or during rolling is 53, as 60 shown in dotted lines, of expanded diameter greater than the blank due to rolling thereof, and my apparatus is further provided with guide rolls 54, and in certain cases only one of these may be needed, but 65 in other cases two may be used as illustrated,

these guide rolls being mounted in the brackets 55, which carry the pivot supporting bolts 56. 57 are bolts which secure my improved front frame to the other parts of the framing and for the purpose of rapidly removing the frame and changing rolls some of these bolts have their heads introduced into T-slots, so that a slight turn on the nuts will allow them to be slid in and out of position in the slotted lugs, while other bolts may have eye heads on pivot bolts, around which they may be turned when the nuts are loosened, and others are usual through-bolts requiring, however, only the screwing or unscrewing of a nut with a few threads so that all are quick-acting fastenings, and as I have only ten bolts which secure the entire front frame to the other structure, the front frame is very easily loosened and taken away from the other parts and as easily secured in place again. To take off the front frame I slide the coupling 58 to the left, loosen or take off the nuts from the bolts 57, rotate or slide some of the ten bolts 57 and then remove the front frame and the reverse operation will install it in place again. By means of my construction I can make the change in one-third the time previously required.

Although I have shown and described my invention in considerable detail, I do not wish to be limited to the exact and specific details thereof, as shown and described, but may use such modifications in, substitutions for, or equivalents thereof as are embraced within the scope of my invention, or as pointed out in the claims.

Having thus described my invention, what I claim and desire to secure by Letters Patent is:

1. In a wheel mill of the class described, having a framing, the combination with the aforesaid framing, of a front frame composed of two integral sections secured thereto and together and provided with wheel mandrel supports, edging rolls, and at least one guide roll mounted thereon.

2. In a wheel mill of the class described, having a framing, the combination with the aforesaid framing of a pair of front frames of integral construction, firmly secured thereto and together and provided with removable wheel mandrel supports, whereby supports of the varying thicknesses may be substituted for said supports, edging rolls, and at least one guide roll mounted thereon.

3. In a wheel mill, the combination therewith of a front frame, comprising a pair of substantially symmetrical integral sections firmly secured together and provided with supports for the wheel mandrel, the edging rolls, and at least one guide roll.

4. In a wheel mill of the class described, having a framing, the combination therewith of a front frame comprising a pair of integral

sections firmly secured together and secured to the other mill framing by quick acting fastenings, such as bolts, most of which operate in slots open at one end for quick assembling and disassembling.

5. In a wheel mill of the class described, having a framing, the combination therewith of a front frame, comprising a pair of integral sections firmly secured together, removably mounted on the other mill framing, and secured thereto by bolts, most of which operate in slots open at one end for quick assembling and disassembling, said front frame being provided with supports for a wheel mandrel, a pair of edging rolls, and at least one guide roll.

6. In a wheel mill, a cylindrical edging roll rotatably mounted in a bracket, a shank on said bracket, a rotatable support in which the shank is slidably mounted, means for rotatably adjusting said support and shank, and means for adjusting said shank longitudinally of said support.

7. In a wheel mill, provided with a front frame, a cylindrical rim edging roll rotatably mounted in a fork or bracket provided with a shank, a support rotatably adjustable in said frame and in which said shank is slidably mounted, and means for adjusting said shank longitudinally of said support.

8. In a wheel mill, an edging roll rotatably mounted on the end of a cylindrical shank, a rotatable sleeve in which said shank is mounted and rotatively secured, a flange or projection on said sleeve provided with a plurality of holes, another plurality of holes in the frame of the mill, a bolt adapted to pass through one of the holes in the sleeve and one in the frame, whereby the edging roll is adjusted radially to the wheel.

9. In a wheel mill, a frame provided with a cylindrical recess, a sleeve rotatably mounted therein, a shank mounted within said sleeve and provided with a feather connection therewith, a nut within said shank, a screw adapted to operate therein, and means for turning the same, said shank having an edging roll rotatably mounted on its end.

50 10. In a wheel mill, a frame provided with a cylindrical recess, a sleeve rotatably mounted therein, a shank mounted within said sleeve and provided with a feather connection therewith, a nut within said shank, a screw adapted to operate therein, said shank having an edging roll rotatably

mounted at its end, said sleeve having a projecting flange provided with means for rotatably adjusting and holding same in position, whereby the edging roll is adjusted and its axis aligned substantially radial to the wheel.

11. In a wheel mill, the combination with the frame, of a sleeve rotatably mounted therein, a shank mounted upon said sleeve and provided with a rotatable roll at one end thereof, means for preventing relative rotation of said sleeve and shank while permitting the longitudinal movement thereof, means for adjusting and holding said shank longitudinally and means for rotating and adjusting said sleeve, whereby said edging roll is adjusted to and from the wheel and its axis is adjusted with respect to the radius of the wheel.

12. In a wheel mill, an edging roll rotatably mounted in a fork and adapted to contact with the side of a wheel rim, a shank on said fork, said shank being provided with an internal screw thread, a screw mounted in said thread, a gear mounted on said screw provided with power means for rotating the same, said shank being mounted in a sleeve provided with means for rotating and clamping it in position desired, whereby said edging roll may be moved inwardly, outwardly or adjusted axially as desired.

13. In a wheel mill provided with a front frame, a rim edging roll rotatably mounted thereon in a fork, an internally screw-threaded shank forming part of said fork, a screw mounted in said thread, power operating means adapted to rotate said screw, a rotatable sleeve mounted in a socket in an integral bracket of the front frame in which said shank is mounted and adapted to be moved longitudinally thereof, a flange projecting from said sleeve and a corresponding flange on the bracket, and means for rotatably adjusting said sleeve and clamping it by the said flanges in position desired.

14. In a wheel mill of the class described, the combination with the top and bottom frames, of an integral front frame secured thereto and provided with wheel mandrel supports, edging rolls and at least one guide roll mounted thereon.

In witness whereof I hereunto affix my signature.

BENJAMIN F. FAUNCE.
